UNITED STATES PATENT OFFICE.

MAXIMILIAN RAHR AND HANS B. BAUER, OF MANITOWOC, WISCONSIN,
ASSIGNORS TO THE WILLIAM RAHR SONS' COMPANY, OF MANITO-
WOC, WISCONSIN, A CORPORATION OF WISCONSIN.

SEED-TESTER.

No. 836,993.

Specification of Letters Patent.

Patented Nov. 27, 1906.

Application filed September 15, 1906. Serial No. 334,817.

To all whom it may concern:

Be it known that we, MAXIMILIAN RAHR and HANS B. BAUER, citizens of the United States, and residents of Manitowoc, in the 5 county of Manitowoc and State of Wisconsin, have invented certain new and useful Improvements in Seed-Testers, of which the following is a specification.

Our invention relates to a seed-tester or 10 germinating device particularly intended for use in making germination tests of barley and other coarse grains in order to test their malting qualities.

In testing coarse seeds or grains to determine 15 their malting qualities it is essential that they be subjected as nearly as possible to the same conditions which obtain in the malt-house during the malting process. In such process the moisture is supplied mainly 20 from above, and the amount supplied varies with the character of the grain, some grains requiring more than others. Various means have been proposed and various testers have been manufactured and put upon the market; 25 but neither the means nor the apparatus heretofore provided have produced good results. In most of these testing devices the receptacle used to contain the grains under treatment is placed in a tray containing water, 30 and the water is supplied by absorption from below; but it is obviously impossible in such case to vary the amount of moisture to suit the requirements of different lots of grain. In these devices the seeds or grains 35 are placed within the receptacle in various quantities, usually more than one layer, so that the seeds are superposed upon each other. Barley grains are practically of uniform size, and in order to secure the best results it is desirable that they should be tested 40 in a single layer instead of the grains being superposed upon each other. It is further desirable to provide a receptacle of a definite size—that is to say, one which will contain a 45 given number of grains of barley and to distribute them in a single layer therein—also to supply the moisture which causes the germination or sprouting to take place from above instead of from below and in such manner 50 that the quantity of moisture may be regulated and adapted to the requirements of the particular lot of grain under treatment.

In the accompanying drawings we have shown our improved tester, Figure 1 being a perspective view, and Fig. 2 a transverse section elevation. 55

In the drawings, 5 represents the body of the receptacle, which is preferably rectangular in form and provided with an upstanding flange 6, within which is a ledge 7, surrounding the said receptacle or germinating-space 8. The bottom of this receptacle is preferably rough, so as to collect and retain moisture. The height of this ledge is substantially equal to the diameter of the grains of 65 barley, or, in other words, the germinating-space is of sufficient depth only to receive a single layer of grains. Upon the ledge is placed one or more sheets of blotter or filter paper 9, and upon this is placed the lid or 70 cover 10. The body 5 and the lid 10 are preferably composed of a porous material, such as earthenware or clay, and provided with escape-apertures, the body having apertures extending through the upstanding 75 flange and ledge practically in the plane of the bottom of the germinating-chamber, as indicated at 11, and the cover having vertical apertures 12 through its body. The bottom of the receptacle is slightly arched along its 80 central portion and sloped toward the apertures 11, so that when the steeped barley is turned into the tester the excess water may drain off therethrough. The apertures 11 also permit the escape of the carbonic-acid 85 gas.

The tester, containing a single layer of grains of barley in contact with the superposed layer of filter or blotter paper saturated with moisture and held in place by the 90 lid or cover, is kept at a suitable temperature, substantially the same as that of the malting compartment or drum, and any number of these testers may be placed in a suitable receptacle, and, if desired, such receptacle may 95 contain moist sheets of filter-paper or other moisture-retaining medium, although we prefer in testing barley to supply the moisture from above. With these testers the progress of germination may be watched, and when 100 completed the mat or sheet of grains may be broken apart and examined, when the unmodified grains will fall out and may be counted, the counting being facilitated by

constructing the germinating-chamber of a size to contain a definite number of grains—say two hundred.

We claim—

- 5 1. A seed-tester comprising a body portion having a germinating-chamber of such dimensions as to hold a single layer of grains and provided with a ledge to maintain a moisture-retaining sheet, and a cover, substantially as described.
- 10 2. A seed-tester consisting of a body portion having an upstanding flange and a ledge within the flange defining a shallow germinating-chamber, and a cover adapted to fit within the flange and to be supported by the ledge, substantially as described.
- 15 3. A seed-tester comprising, in combination, a body of porous material provided with an upstanding flange, a ledge within said

flange adapted to support moisture-retaining sheets, and a cover adapted to fit within the flange and confine such sheets upon the ledge, substantially as described.

4. A seed-tester consisting of a porous body having an upstanding flange, a ledge within the flange, apertures extending through the body in the plane of the arched bottom of the germinating-chamber, and a perforated lid or cover, substantially as described.

In testimony whereof we have hereunto set our hands, this 12th day of September, 1906, at Manitowoc, Wisconsin.

MAXIMILIAN RAHR.
HANS B. BAUER.
